UNITED STATES PATENT OFFICE.

HENRY O. EVANS, OF PHILADELPHIA, PENNSYLVANIA, ASSIGNOR TO
THOMAS DEVLIN & CO., OF PHILADELPHIA, PENNSYLVANIA, A FIRM.

CLAMPING DEVICE.

SPECIFICATION forming part of Letters Patent No. 694,953, dated March 11, 1902.

Application filed November 20, 1901. Serial No. 82,985. (No model.)

To all whom it may concern:

Be it known that I, HENRY O. EVANS, a citizen of the United States, residing in the city and county of Philadelphia, State of Pennsylvania, have invented a new and useful Improvement in Clamping Devices, of which the following is a specification.

My invention consists of an improvement in clamping devices, as will be hereinafter described and claimed.

Figure 1 represents a front elevation of a clamping device embodying my invention. Fig. 2 represents a side elevation, partly in vertical section. Fig. 3 represents a perspective view of the clamping-jaw.

Similar letters of reference indicate corresponding parts in the figures.

Referring to the drawings, A designates the clamping device, which for the purpose of illustration I have shown as applied to a food-chopper B. Said clamping device is provided with the stationary jaw C, which may be bifurcated, as shown, and with the movable jaw D, the latter having its upper or biting face D', such serrated portions being separated by a plain depressed portion E'. The serrated portions D' are situated opposite the members of the bifurcated jaw C. The frame is provided with an upright portion E, extending below the upper jaw C, and at the lower end of the latter is the arm F. It is further noted that the stationary jaw C is comparatively wide, and thereby forms an extended face, while the movable jaw D is provided with the serrated portions opposite the sides of the stationary jaws. Furthermore, the shank of the movable jaw D is narrow and is confined within the slot in the upright E. In this way I provide a durable, yet small, shank for the movable jaw, which is prevented from lateral movement or displacement by the sides of the slot G and also by reason of the engagement of the end of the pin K in the socket J in the lower side of said movable jaw.

Situated within a slot G in the front side of the upright E is the shank H of the movable jaw D, said shank being pivoted at its

rear end, as shown in Fig. 2, to permit the jaw D to move toward and away from the stationary jaw C. In the under side of the jaw D and near its outer end is a curvilinear socket J, said socket being situated opposite the gripping portion of the jaw, or, in other words, the portion of the jaw which is opposed to the stationary jaw C, or at the point of greater leverage.

Passing through a screw-threaded opening in the arm F is the threaded pin K, having a suitable handle L at its lower end, while its upper end is rounded and situated within the socket J, so as to engage the clamping-jaw at the point of the greatest leverage. It is also seen that as the end of the pin K is situated within the socket J undue lateral movement of the clamping-jaw is avoided, since the end of the pin holds the jaw in place.

From the foregoing it will be seen that I provide a clamping device in which one of the jaws although movable is prevented from becoming displaced not only by the pivot upon which it turns, but also by reason of the actuating-pin K engaging the socket thereof, and, furthermore, that the said screw-pin K engages the jaw D at the extreme end of the same, thus applying full power of the screw-pin K at the point of maximum leverage.

Having thus described my invention, what I claim as new, and desire to secure by Letters Patent, is—

In a coupling device, a frame having a stationary jaw and arm, said stationary jaw having lateral extensions, a slot in said frame, a movable jaw having a shank pivoted within said slot, a socket in the lower face of said movable jaw, and a screw-pin carried by said arm and having one end situated within said socket, said socket and slot in connection with the screw-pin and shank serving to prevent lateral movement or displacement of said movable jaw.

HENRY O. EVANS.
